ADAPTER AND HANDLE FOR SPRAY GUNS

Sidney J. Stone, Lyndhurst, Ohio

Application August 10, 1949, Serial No. 109,493

5 Claims. (Cl. 299—89)

1

This invention relates to improvements in an adaptor and handle for use with a spray gun adapted to be attached to the nozzle of a vacuum cleaner or other source of air under pressure.

An object of the present invention is to provide an adaptor to fit between a standard nozzle for supplying air under pressure and a standard spray gun normally used with such a nozzle together with a handle attached to the adaptor with connections to fit the spray gun so that the spray gun may be controlled by a trigger mounted on the handle.

Other objects and advantages of the present invention will be apparent from the accompanying drawings and description, and the essential features will be set forth in the appended claims.

In the drawings,

Fig. 1 is a central sectional view through one type of spray gun showing my improved adaptor and handle attached thereto;

Fig. 2 is a top plan view of the same;

Fig. 3 is a sectional view taken along the line 3—3 of Fig. 1; while

Fig. 4 is a view similar to a portion of Fig. 1 showing a modified form of my device where the handle is constructed in such a way that the air flow is through the handle itself.

My device may be utilized with many types of spray guns which are adapted to be utilized by attachment to the nozzle of a vacuum cleaner or the like which supplies air under pressure. I have chosen to show my device as applied to a spray gun illustrated, described and claimed in the copending application of Franklin P. Morrow and Harold D. Meyers, Serial No. 66,474, filed December 21, 1948, to which reference may be had for a more complete description of the spray gun if necessary or desirable. It is sufficient to state here that the liquid to be sprayed is carried in a standard glass jar 10 fitted with a screw cap 11 to which is attached the spray head 12. Air in the chamber 13, passing through registering openings 14 and 15 located respectively in the spray head 12 and the cap 11, introduces air pressure inside the jar and above the liquid 16 in the jar. This places the liquid under pressure and the escape of this liquid out the discharge pipe 17 is controlled by means of a valve 18 which has a stem 19 extending upwardly through the spray head 12 and provided with an operator button 20 at the top. A spring 34 normally urges the valve 18 toward closed position. It will be noted that there is an opening 21 of greater diameter than the mouth of the discharge pipe 17 so that air escaping from the chamber 13

2

around the liquid stream emerging from the pipe 17 causes a fine spray.

It will be noted that the walls 12a at the rear end of the spray head 12 are of frusto-conical form on the inside flaring rearwardly and outwardly to accommodate a nozzle 22 shown in Fig. 1 as coming from a vacuum cleaner or other similar source of air under pressure. The nozzle 22 has a form complementary to the surface 12a so that the parts normally give a snug fit when used as set forth in the above mentioned copending application of Morrow and Meyers.

My invention provides an adaptor 23 having at its forward end a nozzle 23a, the outside wall 15 of which is of frusto-conical form complementary to the wall surface 12a previously described. The rear end of the adaptor is provided with an interior surface 23b of frusto-conical form and adapted to fit the nozzle 22. I thus make it possible to remove the spray head 12 from the nozzle 22, then placing the adaptor 23 on the nozzle 22 and placing the spray device on the nozzle 23a of the adaptor. The device is then ready to utilize my novel control means.

Secured rigidly to the adaptor 23 is a handle 24 which extends downwardly from the mid-portion of the under side of the adaptor. On the side of the handle 24 nearest the jar 10 there is a projection 25 extending forwardly a short distance and fixed rigidly to the handle. Pivotally mounted on this projection at 26 is a trigger actuator 27. The upper end of this handle 27a is bent toward the rear so as to provide a bell crank of approximately ninety degree angle in form. A double link of bail 28 has its lower end pivotally connected to the arm 27a of the trigger handle at 29. The split side portions 28a of the bail embrace the adaptor 23. The upper end of the bail is passed through a suitable opening 30 in a lever 31 which is pivotally mounted at 32 on a bracket 33 which is rigidly attached to the top forward portion of the adaptor 23. The forward end of the lever 31 has a rounded nose 31a which engages the operating button 20 for 40 the valve stem 19.

The operation of my device should now be apparent. With the parts in the position shown in Fig. 1 and with liquid 16 in the jar 10, and a source of air under pressure provided at the nozzle 22, the operator grasps the handle 24 which is parallel to and to the rear of the jar 10 and not substantially longer than the vertical height of the jar 10. With the hand grasping the handle 24, a pressure is applied by the finger 50 55 of the same hand to the forward side of the

trigger 27. Oscillation of the trigger in a counter-clockwise direction about its pivot 26 will cause the bail 28 to move upwardly causing the rear end of lever 31 to move upwardly and the forward end thereof to move downwardly so that the nose 31a presses on the button 20 and opens the valve 18 so as to actuate the spray. I have thus devised a self contained adaptor and trigger control handle which may be readily adapted to fit between any nozzle and spray gun for the purpose described.

In the modification of Fig. 4, the jar or reservoir 10, its closing cap or cover 11 and the spray head 12 together with the spray actuator button 20 and associated parts are all as described in connection with Fig. 1. The adaptor 34 has a forwardly directed frusto-conical end 34a which is a snug sliding fit within the frusto-conical collar 12a which is the same as the similar numbered part in Fig. 1. Rigidly connected with the adaptor 34 is a hollow handle 35 extending generally at right angles to the central axis through the head 12 and the adaptor 34. In other words, the handle 35 is generally vertical when the device is in use as is the handle 24 of the first described form. The lower end of the handle 35 is flared outwardly as indicated at 35a so as to fit the nozzle 22 which is of the same form as the nozzle 22 shown in Fig. 1 and may be connected with a vacuum cleaner or other similar source of air under pressure. In other words, the parts 22 and 12 of Fig. 4 are like the similarly numbered parts of Fig. 1 but the adaptor portions between these parts have been changed so as to incorporate in Fig. 4 a hollow handle which serves the double purpose of manipulating the spray device while at the same time the flow of air occurs directly through the handle.

The trigger mechanism for actuating the device of Fig. 4 is exactly analogous to that described in connection with Fig. 1. Here the bracket 25' is secured to the adaptor 35 rigidly as was the bracket 25 on the handle 24 in Fig. 1. The trigger 27 has an arm 27a which is connected to the yoke 28 which has the yoke parts 28a passing on opposite sides of the adaptor 34 in the same manner as the first described form shown in Fig. 3. The yoke is pivotally connected at 30 to the rear end of lever 31 which is pivotally mounted at 32 on the bracket 33' which is secured on the adaptor 34 in the same position as the bracket 33 was secured on the adaptor 23.

The operation of the device of Fig. 4 is the same as that of Fig. 1, namely, the operator holds the handle 35 and presses on the trigger 27 which causes the lever 31 to press downwardly on the button 20 to release the spray from the spray head 12.

What I claim is:

1. A device for use with a spray gun assembly having a liquid reservoir with a discharge pipe communicating with said reservoir and a valve controlling discharge from said reservoir through said pipe and an operator for said valve, and said assembly including a spray head connected with said reservoir and with a sleeve-like rear end adapted to fit a nozzle for supply of air under pressure, said spray head providing a chamber at its forward end closely surrounding the mouth of said discharge pipe, there being an opening provided for air ingress to said reservoir from said head and another opening provided for egress of air from said chamber around the mouth of

said discharge pipe, said device comprising an adaptor in the form of a tube having a nozzle at its front end adapted to fit said sleeve-like end of said spray head, said tube having a sleeve-like end at its rear end adapted to fit said air supply nozzle, whereby the exterior surface of said nozzle and the interior surface of said sleeve-like end are substantially identical, a handle rigid with said adaptor and extending at an angle away from it, an actuator carried by said handle, and parts mounted on said adaptor and operatively connected with said actuator and said operator for controlling said valve operator by movement of said actuator.

5 2. The combination of claim 1 wherein said handle extends downwardly from said adaptor, and said actuator is near the upper end of said handle and adjacent said adaptor.

3. The combination of claim 1 wherein said operator for said valve extends out of the top of said spray head, a lever pivotally mounted on top of said adaptor, said lever having one end engaging said operator, said handle extends downwardly from said adaptor, said actuator is near the upper end of said handle, and a link connects said actuator with said lever.

4. A device for use with a spray gun assembly having a liquid reservoir with a discharge pipe communicating therewith and having a final discharge mouth and a valve controlling discharge from said reservoir through said pipe and an operator for said valve, and said assembly including a spray head connected with said reservoir and with a sleeve-like end adapted to fit a nozzle for supply of air under pressure, there being an opening provided for air ingress to said reservoir from said head and another opening provided for egress of air from said head around the mouth of said discharge pipe; said device 30 comprising an adaptor in the form of a tube having a nozzle at its front end adapted to fit said sleeve-like end of said spray head, said adaptor having a sleeve-like collar at its other end adapted to fit said air supply nozzle, a handle rigid with said adaptor intermediate the two ends thereof, an actuator carried by said handle, and parts mounted on said adaptor and operatively connected with said actuator and said operator for controlling said valve operator by movement of said actuator.

5. The combination of claim 4 wherein said handle is hollow, and the hollow of said handle forms a passageway in series between the two ends of said adaptor.

55 SIDNEY J. STONE.
